UNITED STATES PATENT OFFICE.

BARNETT B. WHALEY, OF BROOKLYN, NEW YORK.

TOY.

SPECIFICATION forming part of Letters Patent No. 729,466, dated May 26, 1903.

Application filed May 27, 1902. Serial No. 109,215. (No model.)

To all whom it may concern:

Be it known that I, BARNETT B. WHALEY, a citizen of the United States, residing at Brooklyn borough, New York city, in the county of Kings and State of New York, have invented new and useful Improvements in Toys, of which the following is a specification.

This invention while relating to what may be generally called a "toy" or "bubble-blower" can be considered as serving not only for amusement, but also having practical features, such as lung-testing or lung-developing.

The invention resides in certain novel features of construction, which can be understood from the following specification and claims, and are illustrated in the annexed drawings, in which—

Figure 1 is a side elevation, partly in section, of the toy embodying this invention. Fig. 2 is an edge view sectioned along x x , Fig. 1.

In the drawings is shown the bowl 10 of a pipe. An ordinary clay pipe as found on the market can be used; but in putting this invention on the market a salable outfit is obtained by including therein a wooden bowl with ratan tube or stem. Such details, however, are not to limit the scope of this invention. An attachment 18 can be connected to the bowl by a suitable plug or closure. A plug 16 is shown adapted for insertion into the pipe, or rather its bowl. This plug when made of wood has been found to secure a satisfactory hold or grip to the bowl-wall, so as to remain in place. A slight taper given to the plug will aid proper insertion, and the outer end of the plug can be suitably flanged to serve conveniently as a handle when inserting or withdrawing the plug. The plug is shown provided with a series of perforations or holes, forming passages or outlets for the air when blowing bubbles. These perforations or small channels also serve for holding a supply of suds when the toy is dipped.

A supply of suds being held in the channels and, if desired, a supply of suds or bubble-forming fluid being allowed to settle in the bowl or at the inner face of the plug an amount is obtained sufficient to blow a large bubble or a series or cluster of bubbles. Such

large supply of suds can also be useful in lung testing or competition, which may, in one sense, also be considered as part of the play or amusement furnished by the device. 55 The plug and hook 18 forms a suspending device, upon which is suspended the figure 19 through the frame of the hook 18' engaging with the hook 18.

A figure 19 is shown in Fig. 1, part of 60 which is intended to remain immovable with respect to the bubble, another part being movable or adapted to be swung or moved into and out of the bubble. In stating that the object is fixed to the support does not necessarily 65 mean that it is rigidly soldered or united to the support, as the object may swing from the support, but remain stationary during the bubble-blowing or after the bubble is formed and clings to or at the mouth of the bowl. Say 70 this figure, for example, is made to represent a fisherman having a swinging arm adapted to lift a fish or the like, (shown at 19'.) A string 24, suitably connected to the swinging arm and guided through an eye or loop and 75 having a handle ball or weight 25, can serve to raise the fish, the latter when free dropping by its own weight. The string is long enough to have handle 25 hanging outside the soap-bubble. When the latter is formed, 80 the fixed object 19 is inside the same, while the movable figure or object 19', if the bubble is small enough, hangs outside. The string being suitably pulled, the arm or the fish lifted by said arm will swing or move into 85 the inside of the bubble. When free, the fish will drop back to its lower or starting position.

Of course the representation of a fisherman hauling up a fish merely serves as an example, as other figures—for, example, a monkey moving or sliding along a pole or any variety of acrobatic or other figures—may suggest themselves.

The hook or fastener 18 being centrally located or fastened to the middle of the plug, the bubbles will form or center neatly thereabout.

The suspending device can be made of separable sections. Such separable sections 100 enable the figure, with a bubble surrounding the same, to be removed from the bowl.

What I claim as new, and desire to secure by Letters Patent, is—

1. A toy for producing soap-bubbles comprising a pipe-bowl, a plug extending in and projecting from the bowl and provided with a plurality of channels, a hook depending from said plug, an object movable with respect to the bubble, means connected with the object and engaging with the said hook for suspending the object, and means for moving the object.
2. A toy for producing soap-bubbles comprising a pipe-bowl, a closure-plug extending therein and provided with a plurality of channels, an object movable with respect to the bubble, means for connecting the object to the plug, and means connected with the object and adapted when operated to suitably move the object with respect to the bubble.
3. A toy for producing soap-bubbles comprising a pipe-bowl, a closure-plug extending

therein and provided with a plurality of channels, an object movable with respect to the bubble, means for connecting the object to the plug, and means connected to and depending from the object for suitably operating it with respect to the bubble.

4. A toy for producing soap-bubbles comprising a pipe-bowl, a plug extending in and projecting from said bowl and provided with a series of channels, an object, means connected to the plug for suspending said object, and means connected with the object and depending therefrom and adapted when operated to suitably move the object.

In testimony whereof I have hereunto set my hand in the presence of two subscribing witnesses.

BARNETT B. WHALEY.
